Design No. 169.

Edward Green

"Design for a Fan with Dark Handles."

Patented March 4, 1857.

Nes 769

Theodore Evans, of New York, N.Y.
Letters Patent No 769. Dated March 4th 1856.

The schedule referred to in these Letters Patent, and making part of the same.

To all whom it may concern,

Be it known that I, Theodore Evans, of the City of New York, in the County and State of New York, have produced a new and original Design for the handles of forks and spoons, &c and I do hereby declare that the following is a clear, full, and exact description of the same, reference being had to the accompanying drawing, making part of this specification.

The drawing is in one figure, and is applicable to both sides of the "fork or spoon handle".

I provide a "fork or spoon handle", in any common or known form, and of any kind of metal, and upon its surface or either side, I provide a running head, with a sectional running head a short distance within ^{the foot} at a, and letting the first end at (b) bring the second at or near the tine of the fork or spoon: at or near the tine of the fork or spoon, is a double bow or loose knot from two ribbon ends (see c), this ribbon continues its folds around and round to

42

Dec 769

about two thirds, the length of the handle, when a simple knot is placed on the surface by uniting the two ends of the ribbon. We then continue to extend this ribbon until it meets the end or crown of the fork, spoon, ladle, or knife handle, when it communicates in a simple knot of three loops, with the two ribbon ends extending inward, as represented in the drawing.

Claim.

What I claim as my production, for which I desire Letters Patent, is the peculiar form and figure herein described and set forth as the design for either side of fork, spoon, ladle, and knife handles: the said articles being manufactured of metal of any known kind.
